DESIGN FOR A STIRRUP PUMP

Martin I. Stewart, Jackson Heights, N. Y.

Application June 24, 1942, Serial No. 107,327

Term of patent 3½ years

To all whom it may concern:

Be it known that I, Martin I. Stewart, a citizen of the United States, residing at Jackson Heights, New York, in the county of Queens and State of New York, have invented a new, original, and ornamental Design for a Stirrup Pump, of which the following is a specification, reference being had to the accompanying drawing, forming a part thereof.

In the drawing:

Fig. 1 is a perspective view of stirrup pump, showing my new design.

Fig. 2 is a side elevational view of the same.
Fig. 3 is a top plan view of the same.

The hose shown in Fig. 1 has been omitted in Figs. 2 and 3 for convenience of illustration.

The dominant features of the design reside in the portions shown in full lines.

I claim:

The ornamental design for a stirrup pump, as shown and described.

MARTIN I. STEWART.
